CLAIM

The ornamental design for kettle popper, as shown and described.

DESCRIPTION

FIG. 1 is a front, side perspective view of our new design; FIG. 2 is a front elevation view thereof; FIG. 3 is a rear elevation view thereof; FIG. 4 is a left side elevation view thereof; FIG. 5 is a right side elevation view thereof; FIG. 6 is a top plan view thereof; FIG. 7 is a bottom plan view thereof; FIG. 8 is a front, side perspective view of an alternate embodiment thereof; FIG. 9 is a front elevation view of the alternate embodiment thereof; FIG. 10 is a rear elevation view of an alternate embodiment thereof; FIG. 11 is a left side elevation view of an alternate embodiment thereof; FIG. 12 is a right side elevation view of an alternate embodiment thereof; FIG. 13 is a top plan view of the alternate embodiment thereof; and, FIG. 14 is a bottom plan view of the alternate embodiment thereof.

The broken lines shown in the drawings represent portions of the kettle popper that form no part of the claimed design.

1 Claim, 14 Drawing Sheets
